UNITED STATES PATENT OFFICE.

RAYMOND E. KORTS, OF OSCAR, OKLAHOMA.

UNDER DRILL BIT.

Application filed February 15, 1926. Serial No. 83,271.

This invention relates to well drills, and its object is to provide a new and useful construction of such a drill, provided with means for enlarging the hole made by the 5 drill-bit proper, so as to enable a casing to be lowered into the hole. Such means are known as underreamers, and the present invention, therefore, may be termed a combined drill-bit and underreamer, although 10 the improvements relate to the underreaming means only, which may be used independently of the drill proper.

Such a combined tool is covered by my Patent No. 1,012,563, issued December 19, 15 1911, and the present invention consists in improvements thereover.

The essential features of a tool of this kind are that the underreamer cutter, or cutters, shall be retractable to permit the tool to be 20 withdrawn from the hole through the casing, and that it, or they, shall be positively and solidly held in the body of the tool when in operative reaming position.

According to the present improvements, 25 the cutters, which have grooves in their top rear faces engaging pins which act as fulcrum pins, are moved into and held in their extended outward positions by blocks slideable on inclined surfaces in the cutter-receiving slot of the body and having a wedging engagement with the lower rear ends of the cutters, the effect being to hold the cutters wedged between said blocks and the top 30 of said slot, thus relieving said pins of thrust. Furthermore, in the practical operation of this tool, the space in said slot behind the cutters becomes filled with liquid mud under pressure when the tool is lowered into the well, and since egress for this mud 35 is substantially closed when the cutters are in outward operative position, it serves to prevent them from receding or moving inward into the shank or body, thus maintaining the diameter of the hole at full gage. 40 The mud can, however, be slowly expelled by sustained pressure forcing the cutters inwardly, so that the tool can be retracted from the well.

In my prior patent aforesaid, I showed 45 a tool provided with only one underreamer, while the new tool has two such cutters, but this is not in itself new.

The improvements are illustrated in the accompanying drawing, in which,

50 Figure 1 is a side elevation of the tool;

Figure 2 is a central vertical section of the same;

Figure 3 is a horizontal section on line 3—3 of Figure 1;

Figure 4 is a central vertical section with the underreamers and their appurtenant parts removed;

Figure 5 is a perspective view of one of the underreamer bits;

Figure 6 is a perspective view of the 65 spring for expanding said bits, and

Figure 7 is a perspective view of one of the blocks which close the spaces below the ends of said bits and the body or stock of the tool.

The body or shank 1 of the drill, comprising the bit 2, at its lower end, and the taper threaded stem 3, at its top, has a slot 4 passing entirely through its central portion. Both walls of said slot are provided, adjacent their outer edges, with raised ribs or flanges 5, the inner edges of which constitute downwardly inclined shoulders 6 to retain the underreamer cutters, as will be explained below. Three pins 7 are passed through the 70 body near the top wall 9 of the slot 4 and between the shoulders 6. The bottom wall 8 of the slot is inclined downwardly from each side at a very obtuse angle, and the top wall is likewise inclined downwardly from 75 each side to a central line.

The underreamer cutters 15 have the shape best shown in Figure 5; the sides of the body 10 are recessed to leave the vertical ribs 11, constituting shoulders 12 to engage 80 the shoulders 6 of the drill body, and to leave horizontal shoulders 13, which contact with the lower ends 14 of the ribs 5, when the reamer cutters are in operative position, as shown in Figure 2. The top surface 16 85 of each cutter is beveled at 17, to permit the cutter to rock in the drill body with its top in contact with the top wall 9 of the slot 4, and the cutting end 18 of the bit has a notch 19 in its rear side, to fit on a wedge block 100 20, loosely mounted in said slot on the bottom wall 8. There is, of course, a block 20 on each side, and they are pressed outwardly by a V-shaped flat spring 21, hung on the central pin 7 so that its bent ends 22 abut the rear sides of said blocks, which may be grooved to receive said ends. The rear side 105 of each reamer cutter is provided with a semi-circular groove 23, to fit one of the outer pins 7, which thus constitute fulcrums 110

on which the reamer cutters rock. The outer faces of the cutters are beveled, at 24, so that the cutters will be forced inwardly by the contact of said faces with the lower end 5 of the casing, when the tool is to be withdrawn from the well.

The operation will be clear from the above description and the drawing. When the cutters are expanded by the spring into operative position, they are held solidly between the blocks 20 and the top wall of the slot 4, the pins 7 taking none of the impact force, and the slot is closed against the egress of mud by the blocks, which wedge 15 themselves between the bottom wall of the slot and the top walls of the notches in the cutters, under the influence of the spring, while slightly lifting the cutters. It will be noted that the slot 4 is identical on each side, 20 as are both sides of the cutters and the blocks 20, so that said cutters and blocks are interchangeable. The cutters are readily removable from and insertible in the slot, it being only necessary to push in the blocks 20 and 25 drive out the pins 7, when the cutters can be pulled out past the horizontal shoulders at the lower ends of the ribs or flanges.

The structure described fulfills all the requirements of a tool of this kind, since it 30 does not break or get out of order.

Having thus described my invention, what I claim is:

1. An under-drill bit having a cutter-receiving slot therethrough, the bottom wall 35 of which is inclined downwardly to the center from each side, a pair of underreamer cutters mounted in said slot, means to limit the outward movement of said cutters, and

spring-actuated means slidable on said bottom wall, tending to force the cutters outwardly, to wedge them tightly up against the top wall of said slot and to close the space between the ends of the cutters and said bottom wall. 40

2. A drill bit having a slot extending 45 through the shank thereof, a pair of underreamer cutters mounted to swing in said slot, one on each side, a pair of blocks slidable in said slot, each engaging the lower end of one of said cutters, and a spring to slide 50 said blocks apart, said blocks substantially closing the space behind and between said cutters.

3. A drill bit having a slot extending 55 through the shank thereof, the bottom of said slot being inclined downwardly from each side to the center of the shank and the side walls of said slot being provided with stop shoulders, a pair of underreamer cutters 60 rockingly mounted in said slot and having ribs to engage said shoulders to limit their outward movement, a pair of wedge blocks, one for each cutter, slidable on the said inclined bottom of the slot and engaging a correspondingly shaped notch in the rear lower end of the respective cutter, and a spring tending to force said blocks outwardly, whereby, when the cutters are in operative position, they are firmly wedged between said blocks and the top of said slot. 65

In testimony whereof I have hereunto set my hand.

RAYMOND E. KORTS.
